GEORGE GOULD GOING, OF MIDDLETON, CONNECTICUT, ASSIGNOR TO THE NOISELESS TYPEWRITER COMPANY, OF MIDDLETON, CONNECTICUT, A CORPORATION OF CONNECTICUT.

TYPE-WRITING MACHINE.

1,305,091.

Specification of Letters Patent. Patented May 27, 1919.

Application filed March 31, 1916. Serial No. 27,911.

To all whom it may concern:

Be it known that I, GEORGE GOULD GOING, a citizen of the United States, residing at Middletown, in the county of Middlesex and State of Connecticut, have invented certain new and useful Improvements in Type-Writing Machines, of which the following is a full, clear, and exact description, such as will enable others skilled in the art to which it appertains to make and use the same.

This invention relates to typewriting machines, and more particularly to improved type actions therefor.

One of the objects of the invention is to provide an efficient construction of parts associated to transmit movement from a character key to a movable type carrier.

A further object is to correlate the elements of the type action with the universal bar, escapement mechanism and other features of the typewriting machine to insure permanently reliable co-operation and to permit expeditious adjustment.

Other objects and advantages will in part be noted in connection with the description of an embodiment of the invention illustrated in the accompanying drawings, wherein—

Figure 1 is a fragmentary sectional view of a typewriting machine, indicating particularly the train of connections between one operating key and its type carrier;

Fig. 2 is a fragmentary plan view of certain parts of the type action; and

Fig. 3 is a perspective view of certain power-transmitting elements in the connection of one type carrier.

The invention is shown in the various figures as incorporated in a Noiseless typewriter, to which it is particularly applicable. It is to be understood, however, that certain features of the invention are also capable of use with other styles of machines.

Referring more particularly to the drawings, there is shown a machine frame 1 having a keyboard at the front and a movable platen 2 at the rear, the latter being controlled in its longitudinal letter-space movement by an escapement mechanism 3.

A plurality of finger key levers 4 are fulcrumed at their rear ends in a cross piece 5 and terminate at their forward ends in

character caps 6. The keys are guided in their vertical movement by a comb member 55 7 arranged adjacent the keyboard and are limited in up position by a silent stop 8 and in down position by a similar stop 9 located below an offset extension 10 integral with the more rigid portion 11 of the key lever. 60 The levers are normally held elevated by individual retractile springs 12 tensioned between a depending lug 13 adjacent the fulcrum of each lever and a floating link plate 14 adjustable by a movement of a tie 65 link 15.

Type carriers 16 are arranged radially in advance of the platen 2 and mounted to reciprocate between bed plates 17. The connection between the key lever and the type 70 carrier includes a pull wire 18 fastened to the former and extending vertically to a pivotal connection with a rocking lever 19 fulcrumed at its rear extremity to the depending arm of a bracket 20 mounted for 75 fore and aft adjustment on a curved front piece 21 of the machine frame. The lever 19 is provided with a curved lower edge to engage, by a heel and toe or rocking movement, with the curved upper edge of a horizontally extending short arm 22 of a skeleton bell crank lever 23 pivoted on bracket 20. The long arm of said bell crank lever extends vertically and is fulcrumed medially to a short link 24 having at its fore end a 80 weight 25 (for a purpose to be described), and pivoted at its rear end to the short arm 26 of a T-shaped lever 27 having a fixed axis on the bracket 20 at one end and pivotally connected at its other end with a skeleton 85 link 28, in turn pivoted to an intermediate point of the type carrier 16. The construction of the bell crank lever 23, the arm 24 and link 27, and link 28 is such that, upon actuation of the key lever to effect printing, 90 the long bell crank arm overlaps the arm 26 of the lever 27, and the top arm of the T-shaped lever 27 is in alinement with the link 28 whereby these parts form two straightened toggles to limit the movement 100 of the type carrier toward the platen and to control the speed and pressure of such movement, as will appear.

A U-shaped skeleton universal bar 29 is pivotally supported by a plurality of parallel links 30 and pivotally attached to the

rear end of levers 31 keyed or fixed to a rock shaft 32 having a depending lever 33, the end of which is connected by a link 34 to the escapement mechanism 3.

- 5 29 is arranged for actuation by a straddling piece 35 loosely swiveled on the short arm 22 of the bell crank lever 23 in such relation that, as the rocking lever 19 is pulled downward by the key lever, the escapement mechanism is actuated immediately prior to the termination of the printing movement of the type carrier, but so shortly prior that the inertia of the traveling carriage insures rest of the platen until the printing is effected.

The bell crank lever 23 is normally urged to the position shown in Fig. 1 by a retractile coil spring 36 tensioned between the bracket 20 and the short arm 22 of the lever.

- 20 In order to further hasten the rebound of the type carrier after printing is effected the bell crank lever is provided with a third offset arm 37 movable upward into engagement with a resilient silencing pad 38. The position of the key lever stop 9 is such as to arrest depression of the key prior to the effectuation of the printing operation. The final printing movement of the type carrier is accordingly independent of direct force 25 from the key lever, and is performed by the weight 25, which stores reserve energy in its initial movement and rapidly and forcefully converts such energy into a straightening of the toggles mentioned in the type 30 action, to transmit a relatively great printing pressure to the type carrier, but at relatively slow speed, a characteristic of the noiseless machine.

The structure of the type action is shown 35 more in detail in Fig. 3, wherein the bell crank lever is represented as comprising spaced coincident portions straddling the bracket 20 and adapted to straddle also the double-T-lever 27.

- 40 45 The mounting of the rocking lever 19, bell crank lever 23, and associated T-lever 27 all on the bracket 20 insures permanent adjustment of these parts, while permitting, by fore and aft movement of said bracket, pressure- and distance-equalizing adjustment 50 of the type carrier. The rocking engagement of the lever 19 and short arm 22 of bell crank lever also provides a creeping point of contact in substantially a horizontal line to maximize the power leverage during initial depression of the key lever and thereafter increase the speed of the type carrier toward the platen. The mechanical non-connection between these levers further permits their separation while the printing is 55 effected and insures a retractive rebound of the type carrier immediately thereafter sufficient to clear the type bed 17 for advancement of the next type carrier actuated, even though instant elevation of the former key

lever is not attained. This arrangement renders the machine capable of high speed operation.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, a type carrier, an actuating key therefor, operative connecting means between said elements for moving the former to a predetermined limit to effect printing, said means including three sub-levers having spaced axes of motion, a common adjustable hanger on which said sub-levers are pivoted, and means permitting adjustment of said hanger for varying the limit of movement of said carrier whereby said adjustment is permitted without disturbing the relation of said sub-levers.

2. In a typewriting machine, in combination, a type carrier, an actuating key lever therefor, an operative train of connection between said elements to move the former to a predetermined limit for effecting printing, said means including a pair of sub-levers having rocking engagement upon actuation of said key lever and movable relatively out of engagement after arrest of said key lever, a common adjustable hanger on which said sub-levers are pivoted, and means permitting adjustment of said hanger for varying the limit of movement of said carrier whereby such variation is permitted without disturbing the relation of said sub-levers.

3. In a typewriting machine, in combination, a type carrier, an actuating key lever therefor, operative connecting means between said elements, including two sub-levers having lost motion connection, and a unitary supporting bracket for said sub-levers mounted for adjustment in one direction, said means also including a link pivotally connecting one of said sub-levers and said key lever and disclosed at substantially right angles to the direction of adjustability of said bracket.

4. In a typewriting machine, in combination, a type carrier, an actuating key lever therefor, operative connecting means between said elements, including a pair of sub-levers having rocking engagement upon actuation of said key and movable relatively out of engagement thereafter, and a unitary hanger on which said sub-levers are pivoted.

5. In a typewriting machine, in combination,

- tion, a type carrier, an actuating key lever therefor, operative connecting means between said elements, including two pivoted sub-levers having rocking engagement, one 5 of said sub-levers being connected with said key and having its pivotal axis located in horizontal alinement with the pivotal axis of the other, and a unitary forked bracket having arms on which said sub-levers are 10 mounted.
6. In a typewriting machine, in combination, a rectilinearly movable type carrier, a pivoted actuating key therefor, a pull member attached to the latter, a thrust member 15 attached to the former, three sub-levers, including a bell crank lever, operatively connecting said members, and a single supporting bracket for said sub-levers.
7. In a typewriting machine, in combination, a rectilinearly movable type carrier, an actuating key therefor, operative connecting means between said elements, including two sub-levers having a lost motion connection, and a stamped metal bracket support for 25 said sub-levers having spaced arms at the extremities of which said sub-levers are pivoted, one of said sub-levers straddling its supporting arm and the supporting arm for the other being offset to aline the latter 30 sub-lever with the first.
8. In a typewriting machine, in combination, a rectilinearly movably type carrier, an actuating key therefor, operative connecting means between said elements, including two sub-levers having a lost motion connection, 35 and a bracket support for said sub-levers having spaced arms at the extremities of which said sub-levers are pivoted, and between which said sub-levers are normally positioned.
9. In a typewriting machine, in combination, a type carrier, an actuating key therefor, operative connecting means between said elements, including two sub-levers having rocking engagement, and a bracket support for said sub-levers having two depending spaced arms with relatively offset extremities on which said sub-levers are pivoted, and having a third arm for attachment 40 to a rigid part.
10. In a typewriting machine, in combination, a type carrier, an actuating key therefor, operative connecting means between said elements, including two sub-levers having a lost motion connection, a bracket support for said sub-levers having spaced arms on which said sub-levers are pivoted and between which said sub-levers are normally positioned, and a coil return spring for one of said sub-levers attached to 45 said support and also positioned between said spaced arms thereof.
- In testimony whereof I affix my signature, in the presence of two witnesses.
